(57) **CLAIM**

The ornamental design for a fishing lure holster, as shown and described.

DESCRIPTION

FIG. 1 is a front perspective view of a fishing lure holster, showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top view thereof.

FIG. 7 is a bottom view thereof.

FIG. 8 is a bottom perspective view thereof; and,

FIG. 9 is a perspective view thereof, in use condition.

The broken lines, shown in the drawings represent unclaimed portions of the design and form no part thereof.
